UNITED STATES PATENT OFFICE

2,564,110

EDGE-LIGHTED SIGN

James A. Howenstein and Kenneth F. Smith,
Lima, Ohio, assignors to Neon Products, Inc.,
Lima, Ohio, a corporation of Ohio

Application May 13, 1949, Serial No. 93,036

5 Claims. (Cl. 40—130)

1

This invention relates to edge-lighted signs, and more particularly relates to a base for an edge-lighted sign panel.

An object of this invention is to provide a base for an edge-lighted sign panel which is economical to manufacture.

A further object of this invention is to provide a base for an edge-lighted sign panel to which the panel can be removably attached.

A further object of this invention is to provide a base for an edge-lighted panel made from readily moldable or formable plastic.

A further object of this invention is to provide a base for an edge-lighted sign panel made of transparent resin or the like in which a lighting fixture may be enclosed and hidden.

A further object of this invention is to provide a base for an edge-lighted panel which is in the form of a hollow elongated shell of transparent resin or the like which can cover an elongated fixture, the shell containing an elongated lengthwise depression or groove formed medially of the upper face and having a coat of paint on its inner surface covering the inside of the shell with the exception of the portion thereof opposite or immediately below the groove, the groove being adapted to receive an edge-lighted panel so that light from the fixture can reach the panel through the unpainted section, the lighting fixture however being hidden by the paint.

The above and other objects and features of the invention will in part be obvious and will in part be apparent from the following detailed description and the drawing in which:

Figure 1 is a view in side elevation, of an edge-lighted sign having a base constructed in accordance with an embodiment of this invention, the base being shown partly broken away and in section to reveal details of construction;

Fig. 2 is a top plan view of the sign illustrated in Fig. 1, the base being shown partly broken away to reveal details of a backing plate;

Fig. 3 is a sectional view taken along a line III—III in Fig. 1;

Fig. 4 is a transverse sectional view of a shell which forms a portion of the base, the shell being shown before the internal coat of paint is applied;

Fig. 5 is a transverse sectional view of the shell following application of paint to the interior of the shell; and

Fig. 6 is a fragmentary view in side elevation, partly broken away and in section, showing a base for a sign panel constructed in accordance with a second embodiment of this invention.

In the following detailed description and the drawing, like reference characters indicate like parts.

2

In Figs. 1 to 3 inclusive, an edge-lighted sign is shown which includes a hollow shell 10 adapted to house a lighting fixture 12. A lengthwise groove or depression 13 is formed in the upper face or top of the shell, and in this groove a panel 14 of glass, transparent plastic, or the like, is mounted edgewise. Light passes through the groove and illuminates the panel through the edge thereof. In other words the panel 14 is edge-lighted or illuminated.

The shell 10 is open at its bottom and a base plate 16 coextensive with the bottom is attached to the shell and acts as a support and closure for the shell and as a mounting for the lighting fixture 12.

The shell may be formed from clear transparent resinous material, such as a methyl methacrylate resin, which may be shaped as shown in Figs. 4 and 5 to have an upper face 17 in which the groove 13 is formed and downwardly extending walls 18 forming a hollow cup-shape. A peripheral outwardly extending flange 19 may be provided for attaching the shell to the base plate.

The interior of the shell is coated with paint, as indicated at 21 in Fig. 3, with the exception of the portion of the shell opposite the lengthwise groove 13 which is left clear to permit light to reach the edge of panel 14. Figs. 4 and 5 illustrate progressive stages in the formation of the shell. A masking strip of gummed tape 22 or the like is attached to the inside of the shell opposite the groove 13 before the interior of the shell is painted. Then, while the strip 22 is in place, the interior of the shell is painted with a translucent or relatively opaque paint so that when the sign is in use, the illuminating fixture 12 may be hidden behind the paint. Then, the masking strip 22 may be removed, so that when the shell is completed, all of the interior surface thereof is coated with paint except that portion which is opposite or immediately below the lengthwise groove.

The backing plate 16 serves as a mounting for the lighting fixture 12 which may be of the common fluorescent tube type, and a starter 23 for the lighting tube.

Appropriate electrical conductors, not shown, may extend through the base plate 16 for connecting the tube to a supply of electrical energy.

As shown in Figs. 1 and 3, the base plate 16 may be formed from a flat panel of metal or the like. The longitudinal edges of the plate 16 may be bent upwardly to form flanges 24 which fit inside the walls 18 while the ends of plate 16 are flat and support ends of the shell 10. A U-shaped retainer 26 is attached to the panel 14 with flanges thereof extending upwardly inside the walls of the shell, and screws 27 may extend

through the walls of the shell into the flanges of the retainer 26 to hold the shell and plate assembled.

As shown in Fig. 1, the panel 14 is flat and has a lower edge 28 which fits into groove 13. Lettering 29 may be etched or otherwise recessed in the plate 16 in the usual manner. At either end of the groove 13, a slotted post 31 is attached to the upper face of the shell, and the slots of the posts are adapted to embrace vertical edges of the panel 14 to hold the panel erect.

The panel may be removable or may be attached to the groove by means of any appropriate clear cement which will permit light from the fixture 12 to reach the panel 14.

In Fig. 6 is shown an alternate embodiment of the invention in which a shell 32, generally of the same construction as the shell 10, is supported by a base plate 33. The plate 33 has an upstanding peripheral flange 34 to which a pair of angle-shaped retainer elements 36 and 37 are attached by means of screws 38. One flange of each of the angle-shaped retainers is attached to the flange 34 while the other flanges of the retainers 36 and 37 are spaced to form an inwardly extending peripheral slot adapted to embrace a flange 39 of the shell 32.

In the embodiment shown in Fig. 6, short slotted posts 41, only one of which is shown, embrace the ends of an edge-lighted panel 42. The posts 41 are substantially shorter than the posts 31 shown in Figs. 1 to 3 inclusive, and the panel shown in Fig. 6 is adapted to be cemented in place while the panel shown in Figs. 1 to 3 may be removable.

The paint used for coating the inside of the shells may be translucent so that the entire shell glows when the sign panel is illuminated or the paint may be relatively opaque. If desired, appropriate advertising indicia or the like may be painted on the inside walls of the panel so as to be illuminated by the lighting fixture thereof.

The embodiments of this invention disclosed in the drawings and described above are subject to modification within the scope of the appended claims.

Having described our invention what we claim as novel and desire to secure by Letters Patent is:

1. An illuminated sign which comprises a hollow elongated shell of transparent plastic material having a closed top and an open bottom provided with a removable cover plate, an elongated lighting fixture inside said shell and mounted on said cover plate, the closed top of said shell having a groove extending lengthwise thereof, and a transparent panel mounted edgewise in said groove, whereby said panel receives edgewise illumination from said lighting fixture through the wall of said groove, a coating on said housing adapted to substantially obscure said lighting fixture, said coating terminating at an uncoated strip along the groove, and means for supporting said panel in upright position on said shell.

2. An illuminated sign which comprises a hollow elongated shell of transparent plastic material having a closed top and an open bottom provided with a removable cover plate, an elongated lighting fixture inside said shell and mounted on said cover plate, the closed top of said shell having a groove extending lengthwise thereof, a transparent panel mounted edgewise in said groove, whereby said panel receives edgewise illumination from said lighting fixture

through the wall of said groove, a coating on said housing adapted to substantially obscure said lighting fixture, said coating terminating at an uncoated strip along the groove, and a vertically slotted post attached to the shell at each end of said groove, the slots in the posts facing each other for receiving opposite edges of the panel.

3. An illuminated sign which comprises a hollow elongated shell of transparent plastic material having a closed top and an open bottom provided with a removable cover plate, an elongated lighting fixture inside said shell and mounted on said cover plate, the closed top of said shell having a groove extending lengthwise of the top face thereof, the bottom wall of said groove being transparent, a transparent solid panel mounted edgewise in said groove to receive edgewise illumination through said groove, said panel having indicia on the face thereof which is lighted by illumination transmitted through said edge, and a layer of paint on the interior surfaces of the shell bounding the transparent bottom of said groove, whereby the lighting fixture is hidden.

4. An illuminated sign which comprises a hollow elongated shell of transparent plastic material having a closed top and an open bottom provided with a removable cover plate, an elongated lighting fixture inside said shell and mounted on said cover plate, the closed top of said shell having a groove extending lengthwise of the top face thereof, the bottom wall of said groove being transparent, a transparent solid panel mounted edgewise in said groove to receive edgewise illumination through said groove, said panel having indicia on the face thereof which is lighted by illumination transmitted through said edge, and a layer of translucent paint on the interior surfaces of the shell bounding the transparent bottom of the groove, whereby the lighting fixture is hidden and the shell and the panel are illuminated by the lighting fixture.

5. An illuminated sign which comprises a hollow elongated shell of transparent plastic material having a closed top and an open bottom provided with a removable cover plate, an elongated lighting fixture inside said shell and mounted on said cover plate, the closed top of said shell having a groove extending lengthwise of the top face thereof, the bottom wall of said groove being transparent, a transparent solid panel mounted edgewise in said groove to receive edgewise illumination through said groove, said panel having indicia on the face thereof which is lighted by illumination transmitted through said edge, and a layer of substantially opaque paint on the interior surfaces of the shell bounding the transparent bottom of said groove, whereby the lighting fixture is hidden.
